ATTY

UNITED STATES PATENT OFFICE.

CHARLES F. MCBEE, OF ATHENS, OHIO.

LOOSE-LEAF FILE.

1,151,806.

Specification of Letters Patent. Patented Aug. 31, 1915.

Application filed May 15, 1914. Serial No. 838,840.

To all whom it may concern:

Be it known that I, CHARLES F. MCBEE, a citizen of the United States, residing in Athens, county of Athens, and State of Ohio, 5 have invented a new and useful Improvement in Loose-Leaf Files, of which the following is a specification.

The object of my invention is to provide a loose leaf file of simple, strong and durable 10 construction, and which may be quickly and easily operated for the purpose of removing certain sheets from the file or for inserting sheets therein, at any desired position.

A further object is to provide such a file 15 with a secure lock on each end thereof, both of said locks being released simultaneously by one operation, and the locking of the same being accomplished automatically by the closing of the file.

20 My invention consists in the construction, arrangement and combination of the various parts of the device, whereby the objects contemplated are attained, as hereinafter more fully set forth, pointed out in my claims and 25 illustrated in the accompanying drawings, in which—

Figure I shows a perspective view of my file, the dotted lines indicating its appearance when opened for the reception of 30 sheets. Fig. II is an elevation view showing the position of the parts when the file is nearly closed; and Figs. III and IV show detail views, partially in section, of the manner of locking of the plates, Fig. III 35 showing the positions of same just before locking.

Referring to the accompanying drawings the reference numerals 10 and 11 indicate the upper and lower covers, respectively, of 40 my file, same being flexibly joined to the customary back 12.

45 My improvement is in the nature of an attachment adapted to be secured to the inner surface of the back 12, and said back may be specially formed to receive it, if desired, or the body portions of my device may be formed to be attached to any customary or ordinary back.

The preferred form of my attachment, as 50 shown in the drawings, consists of two body plates 13 and 14, hinged centrally at 15 and 16, said body plates covering practically all of the inner surface of the cover 12, the line of movement of the two plates, as denoted by the hinges, being centrally and longitudinally of the back. The end of the plate

13 is turned inwardly, at right angles to the body portion, on each of its ends so as to provide ears 17 and 18 respectively, said ears projecting beyond the center between the 60 covers when the file is closed. The plate 14 is likewise turned at its ends to provide the ears 19 and 20, the ears 17 and 19, and the ears 18 and 20, being designed to overlap and to be in light engagement with each 65 other when the file is closed. The ears 17 and 18 are each provided with an orifice and a rod 21 is operatively secured therein as shown. The said rod is actuated by a spring 22, mounted between and bearing against 70 the collar 22', which is fixed on the rod, and the adjacent ear 18, the circular locks, or stops, 23 and 24, confining the rod within its bearings (the said orifices) and limiting the movement of the rod in one direction and 75 determining the normal position thereof as caused by the spring 22. The limit of movement of the rod when it is forced against the spring is determined by the push lug 25 secured to the outer end thereof as shown. 80

The ears 19 and 20 are each provided with circular orifices 26 and 27 respectively, designed to receive the circular lugs 23 and 24 respectively, and extending outwardly through the ears from each orifice is a slot, 85 28 and 29 respectively, designed to receive the rod 21. Surrounding the outer end of the slots 28 and 29 the ears 19 and 20 are beveled to a sharp edge for purposes herein-after set forth. 90

The numerals 30 and 31 indicate posts, curved as shown if desired, secured to the plate 13 the ends of which are received in orifices 32 and 33, respectively, in the plate 14 when the file is closed, and the numerals 95 34 and 35 indicate like posts on the plate 14 the ends of which are received in orifices, 36 and 37 respectively, in the plate 13 when the file is closed.

The plates 13 and 14 are secured to the 100 back 12 in any desirable manner.

In practical operation the file being open perforated sheets are placed on either set of posts desired. The covers are then closed, the sharpened edges of the ears 19 and 20 engaging between the ears 17 and 18 respectively and their respective lugs 23 and 24 on the rod 21. Pressure to bring the backs together forces the ears 19 and 20 into the minute spaces between the ears 18 and 19 110 respectively and their respective lugs, thus forcing the rod 21 against its spring 22 and

forcing an opening. The slots 28 and 29 receive the rod 21 which passes therethrough and when the orifices 26 and 27 are in position under their respective lugs 23 and 24 5 the spring 22 forces the rod backward, the said lugs entering their respective orifices and seating therein, the lugs butting against their respective ears 19 and 20. It is obvious this action and the construction of the 10 parts form a practical and satisfactory lock for each end of the file. When it is desired to release the locks to open the file to receive or to take out sheets the operator pushes on the lug 25 moving the rod 21 and forcing 15 the lugs 23 and 24 out of their respective seats and the rod 21 passing from engagement with the ears 19 and 20 through the slots 28 and 29 respectively.

My device, as before stated, is in the 20 nature of an attachment adapted to be secured to any ordinary set of covers and backs, and it is preferably used with a body portion, as shown, constituting a support for the working parts. It is obvious, however, 25 that this body portion may be made of several sections centrally hinged, or the hinges might be omitted depending on the flexibility of the back to operate as a hinge, or the body portion might be omitted and 30 each end of the file be provided with lugs with right angular ears to receive a spring actuated rod performing the functions of the rod as shown, and I therefore desire it to be known, that any of these constructions 35 are contemplated by my invention and are included as a part of this application, the principle feature of which is the simultaneous locking and unlocking of the two ends 40 of a file by a common means, in the manner set forth.

Having thus described my invention what I claim and desire to secure by Letters Patent of the United States is:

1. A loose leaf file comprising covers and 45 a back, spaced pairs of ears upstanding from the back, those of each pair being adapted for overlapping when in closed position, each ear being provided with an orifice and one ear of each pair being formed with a 50 slot leading from the orifice to the edge of the ear, said edge of the ear being beveled to provide a sharpened wedge portion, a single rod slidible in the orifices of the unslotted ears and projecting at each end from 55 the ears, a hand lug on one projecting end, a lock fixed on the other projecting end of the

rod, a second lock fixed on the rod between the ears and on the opposite end portion, said locks being adapted to enter the orifices of the slotted ears when brought into coincidence therewith, and leaf-engaging posts on the back.

2. In a loose leaf file, hingedly connected body plates each having its ends upturned to provide opposing ears, the ears of one plate being orificed and the ears of the companion plate being provided each with an orifice and a slot leading therefrom to the edge of the ear which edge is beveled to form a sharpened wedge portion, leaf-engaging posts on the body plates, a rod slidible in the orifices of the first specified ears and projecting therefrom at its ends, a collar fixed on the rod adjacent one of the ears, a coiled spring encircling the rod between 75 and bearing against the collar and the adjacent ear, a hand lug on one projecting end of the rod, a lock fixed on the opposite projecting rod end, and a collar fixed on the rod between the ears and adjacent the ear opposite from the one supporting the spring.

3. In a loose leaf file a pair of body members secured to the inner surface of the back and hinged together longitudinally at the central line of the back; an ear on each end 85 of each body portion, the ears on similar ends of the body members mating when the file is closed; a rod slidably mounted in orifices in the ears of one body member and slots in the ears on the other body member to engage the said rod; and an orifice at the ends of said slots; lugs on the rod to engage in the said orifices when the file is closed and form a lock to bind the mating ears together; a spring on said rod to hold the said 95 lugs in said orifices and means to actuate said rod so as to withdraw the lugs simultaneously from their seating orifices, the ears provided with the said slots being beveled to a point adapted to engage between their mating ears and the said lugs 100 for forcing the rod against the spring, when pressure is applied, for automatically locking the file when the same is closed; means on the body members for receiving and retaining perforated sheets to be placed in the file, substantially as shown and described.
